UNITED STATES PATENT OFFICE.

FRANKLIN W. OEHRL, OF PHILADELPHIA, PENNSYLVANIA, ASSIGNOR TO OEHRL
BROTHERS COMPANY, OF PHILADELPHIA, PENNSYLVANIA, A CORPORATION OF PENNSYLVANIA.

DESIGN FOR A KNITTED FABRIC.

Application filed March 8, 1924. Serial No. 8,879. Term of patent 7 years.

To all whom it may concern:

Be it known that I, FRANKLIN W. OEHRL, a citizen of the United States, and a resident of Philadelphia, county of Philadelphia, State of Pennsylvania, have invented a new, original, and ornamental Design for a Knitted Fabric, of which the following is a specification, reference being had to the accompanying drawing showing my design.

The figure of the drawing is a plan view of a portion of fabric showing my new design.

The design is intended to be repeated lengthwise substantially as indicated in the drawing.

I claim:

The design for a knitted fabric substantially as shown and described.

In testimony whereof I have hereunto signed my name this 5th day of March, A. D. 1924.

FRANKLIN W. OEHRL.
